UNITED STATES PATENT OFFICE.

LAVANT V. CAUKIN, OF MENASHA, WISCONSIN, ASSIGNOR TO MENASHA PRINTING & CARTON CO., OF MENASHA, WISCONSIN, A CORPORATION OF WISCONSIN.

METHOD OF MAKING OFFSET COLOR PLATES.

No Drawing.

Application filed March 17, 1923. Serial No. 625,879.

To all whom it may concern:

Be it known that I, LAVANT V. CAUKIN, a citizen of the United States, residing at Menasha, in the county of Winnebago and State of Wisconsin, have invented a certain new and useful Improvement in Methods of Making Offset Color Plates, of which the following is a specification.

Off-set printing occupies a very important field in the printing art, but the production of its necessary color plates has been a very serious problem and at times prohibitive, this because, as heretofore commercially practiced, it has been necessary to use from six to ten or more colors to reproduce the colors of a given picture, each of these colors requiring a separate printing plate and a large amount of re-touching or hand manipulation which in turn destroys the accuracy of the copy as compared with the original picture.

The object of this invention is to make off-set color plates which are so absolutely accurate in reproducing the original copy that as good results can be obtained with four, or even three, plates as with six to eight under the old methods, and to produce these plates at a cost per plate materially below that of the prior art.

The invention consists in a method of attaining the foregoing and other objects, which will be hereafter more fully set forth in the specification and claims.

Assume that a given multiple colored picture is to be reproduced by the method of this invention. It is set up before a camera and, assuming four colors are to be used in the finished product, four conventional half-tone negatives corresponding, respectively, to the colors of yellow, red, blue and black, are made of it by standard photo-engraving methods. A print of each of these four negatives is conventionally made on a separate copper plate and etched in the ordinary manner. This set of plates is then used serially in the ordinary photo-engraving method to superimpose one color upon the other in the regular standard order to produce one proof of the combination of the colors belonging to the different plates; in other words, to make a sample of the final product which is to be produced in the commercial printing. This composite color proof is sent to the customer for approval as to whether the finished

product shown by it is satisfactory. If the customer calls for any changes, they are made upon the separate plates by old, well-known methods and a new composite proof or proofs submitted to the customer until his final approval is given. The steps down to this point are old, and in present use and the plates could be conventionally used for letter-press printing which is, however, much more expensive than off-set printing. In order to adapt these half-tone color plates for use in off-set printing with the same physical results as though they were used in letter-press printing while producing the off-set plates at a very great saving in expense over the old methods heretofore used in producing off-set plates, the following procedure of this invention is followed:

After the product sample has been approved by the customer, a proof is made of each plate in its own color for the use hereafter described. An ordinary black ink proof is pulled from each plate on very white double-coated enamel paper—such, for instance, as De Jonge paper—which will give in the proof an accurate showing of all details of the copper plate. Whatever paper is used must be tough and non-stretchable in order to insure register of the plates later produced from these proofs.

Having obtained these accurate black and white proofs, a camera is set up where it is substantially absolutely free from vibration; each of the black and white proofs placed in succession in exactly the same spot on the copy board before the camera, so mounted that it cannot be moved between photographs of the successive plates—this to insure a perfect register of the successive negatives to be made one of each proof. With this equipment a wet plate negative is made of each of the black ink proofs. Best results are obtained in producing these wet plate negatives by giving each negative glass a double coat of collodion, instead of one in accordance with conventional practice, just before its immersion in the conventional silver bath, one coating of collodion being drained from one side (or end) of the glass, the other coating applied while the first coating is still tacky, being applied and drained from the opposite side (or end) of the glass.

Having obtained a set of wet plate nega-

2
tives—preferably on these double collodion coated plates—one for each color which is to be used in making the final finished work, the negatives, each accompanied by the proof in its own color, taken from its own copper plate as heretofore described, is turned over to a commercial lithographer who proceeds by conventional methods to print these plates one at a time onto any conventional lithographers' metal. The lithographer uses the colored proofs furnished him as just described to guide him in the amount of ink he uses on the plates as he runs them so that the finished products will correspond with the proof previously approved by the customer.

Owing to the fact that most printers' black inks contain a large amount of blue pigment, invisible to the eye but very visible to a camera, best results are obtained in making the so-called black proofs, heretofore referred to, by adding to the commercial ink with which the black proofs are made approximately 5% in volume of yellow ink and 5% in volume of red ink and thoroughly mixing it in. This result is still apparently black ink but the product is much more dense in color for the camera to pick up, with the result that much sharper images will be reproduced on the negatives which go to the lithographer.

Attention is again called to the urgent desirability of doing the photographing of the half-tone copper plate proof where substantially no vibration takes place. If this instruction is not adhered to, the photographs will not be accurate in tone value, and the finished printing will be correspondingly defective.

40 In actual commercial work the described method reduces the cost of producing the plates required for a given piece of work from fifty to sixty-five per cent.

45 The use of the single color proofs from the original half tone plates in checking the inking of the final lithographic-offset color plates is quite important because the printer can, by materially varying the inking of a single offset color plate, materially distort the coloring of the finished product and perhaps entirely destroy its utility.

Having thus described my invention, what I claim as new and desire to secure by Letters Patent is:

55 1. The herein-described method of producing off-set color plates consisting in first making conventional half-tone plates of the picture to be reproduced, one for each color

entering into the finished product, which when tested in combination by conventional methods produce the desired finished product; taking an accurate black and white proof from each plate, making accurate full detail registering negatives of the respective black and white proofs, and then conventionally using said negatives to produce conventional lithographic plates thereof.

2. The herein-described method of producing offset color plates consisting in first making conventional half-tone plates of the picture to be reproduced, one for each color entering into the finished product, which when tested in combination by conventional methods produce the desired finished product; taking an accurate black and white proof from each plate; making accurate, full detail, registering, wet plate double collodion coated negatives of the respective black and white proofs, and then conventionally using said negatives to produce conventional lithographic plates thereof.

3. The herein-described method of producing off-set color plates consisting in first making conventional half-tone plates of the picture to be reproduced, one for each color entering into the finished product, which when tested in combination by conventional methods produce the desired finished product; taking an accurate black and white proof from each plate, using commercial black ink with about five per cent of red and five per cent of yellow ink, both by volume, mixed therein; making accurate, full detail, registering, wet plate double collodion coated negatives of the respective black and white proofs, and then conventionally using said negatives to produce conventional lithographic plates thereof.

4. The herein-described method of producing offset color plates consisting in first making conventional half-tone plates of the picture to be reproduced, one for each color entering into the finished product, which when tested in combination by conventional methods produce the desired finished product; taking an accurate black and white proof from each plate on tough, non-stretchable, very white, double coated enamel paper; making accurate, full detail registering negatives of the respective black and white proofs, and then conventionally using said negatives to produce conventional lithographic plates thereof.

In witness whereof, I have hereunto subscribed my name.

LAVANT V. CAUKIN.
